UNITED STATES PATENT OFFICE

ALBERT M. PLUMB, OF DENVER, COLORADO.

ORE-SEPARATOR.

1,202,219.

Specification of Letters Patent. Patented Oct. 24, 1916.

Application filed June 30, 1913. Serial No. 776,529.

To all whom it may concern:

Be it known that I, ALBERT M. PLUMB, a citizen of the United States of America, residing at the city of Denver, State of Colorado, have invented a certain new and useful Ore-Separator, of which the following is such a full, clear, and exact description as will enable any one skilled in the art to which it appertains to make and use the same, reference being had to the accompanying drawings, forming part of this specification.

This invention relates to improvements in ore separators of the character described in my Patent No. 1,079,362, issued November 25, 1913.

I have found that in separating certain classes of material, the production of a slightly more violent agitation of the particles adjacent to the tailings discharge opening than in other portions of the column to which the material is fed lessens the liability of any particles of concentrates being carried with the tailings from the point of feed to the tailings discharge opening before they have found their way to a point below the level of this opening. It is to this discovery and means for utilizing it that this application is more particularly directed.

Other objects and advantages of the invention will be set forth in the following more detailed description.

In the drawings accompanying this application and forming a part thereof, Figure 1 is a front view of the separator, partly in elevation and partly in section, and Fig. 2 is a transverse vertical section.

The separating chamber comprises side and end walls 1, the ore supporting screen 2, and the baffle plate or partition 10 inclined at its upper edge.

3 designates the walls of the air chamber beneath the separating chamber, and 4, 45 screen supporting members extending across the upper portion of the air chamber.

5 is a tapering air nozzle communicating with the air chamber by means of a narrow slot 6 extending throughout the entire length of said chamber. The separating chamber is provided with a concentrate discharge opening 7 and a tailings discharge opening 8.

11 are guide plates extending across the bottom of the separating chamber.

The material to be separated is placed

in a container 12 which is provided with discharge spouts 16 which terminate in a plane substantially parallel with the inclined portion of the partition 10. The container 12 is slidably mounted on the separating chamber and its position may be shifted by means of the threaded shafts 17 operated by the hand wheels 9 to vary the distance between the ends of the discharge spouts 16 and the inclined face of the partition 10 to regulate the rate of feed of material to the separating chamber. The whole separator is supported by a frame 13, as shown, preferably in such position that the screen 2 will be level.

14 represents one of the cap screws by means of which the separator may be attached to the support, and 15 a set screw by means of which the separator may be tilted slightly on its support, the purpose of this tilting being to cause the material in the column which receives the feed to assume a position in which it will be slightly deeper and consequently heavier in the space adjacent to the partition 10 than near the tailings discharge opening 8. This difference in depth must be very slight, being only sufficient to cause a slightly greater volume of air to pass through the portion of material near the tailings discharge opening but, at the same time, not permit so much air to pass through as to prevent proper agitation of the remaining material in the separating chamber.

In the operation of the apparatus, material to be separated is supplied to the portion of the separating chamber between the partition 10 and the discharge opening 8, and intermittent impulses of air are supplied through the air chamber imparting an up and down or jiggling motion to the particles. As a result of this action, the ore particles having a greater specific gravity than the particles of tailings will gradually displace the latter particles with the result that immediately above the screen a layer of material will be formed consisting only of ore particles, or concentrates, and at the top of the bed, a layer will be formed consisting only of tailings. Between these two layers will be a mixture consisting of particles of tailings and ore particles. If additional material is supplied to the separating chamber, the ore particles in this material will find their way downward with the result that other ore particles will be

forced under the partition 10 thus raising the surface of the concentrate column and causing concentrates to be discharged at the opening 7. The added tailings will also 5 cause the upper surface of the tailings column to rise high enough to overflow at the discharge opening 8.

It will be noted that the discharge opening 8 is somewhat higher than the concentrates opening 7, but, on account of the 10 difference in the quality of material in the two columns, the weight of these two columns will be substantially equal per unit of horizontal cross sectional area, thus causing 15 the air pressure to be distributed substantially evenly over the entire lower surface of the bed of material in the separating chamber. The motion of the ore particles downward laterally under the partition 10 20 and upward to the discharge opening 7 is produced by displacement with the result that the "middlings" stratum is always confined between the partition 10 and the walls of the concentrating chamber and has no 25 lateral motion, thus making it impossible for any material of this character to be discharged.

The inclination of the ore supporting screen, for the purpose hereinabove described, is so slight that the general principles of operation of the apparatus are 30 the same as in the apparatus described in my previous application hereinbefore referred to.

35 In the operation of the apparatus some very fine particles of ore find their way through the supporting screen and drop down to the bottom of the air distributing nozzle and, in order to remove these particles and to prevent their interference with the ingress of air, I connect the air supply pipe 18 to a T-joint 19, as shown, and provide a plug 20 having an opening which is sufficiently small to allow these ore particles to escape but not to substantially interfere with the production of the proper air pressure in the air chambers.

Having fully described my invention, what I claim as new and desire to secure by 50 Letters-Patent of the United States is:

1. In an ore jig, a separating chamber provided with means for maintaining at least two separate columns of material communicating at their lower ends and with 55 discharge openings for each column, the relative heights of the discharge openings being such that the weights of the columns of material, when each extends to the level of its discharge opening, will be substantially proportional to their horizontal cross-sectional areas, means for agitating the material in the separating chamber and means 60

whereby the material adjacent to the tailings discharge opening will be agitated to a greater degree than other portions of material in the same column. 65

2. In an ore separator, a separating chamber having a reticulated bottom and provided with means for maintaining at least two separate columns of material thereon 70 communicating at a point near said bottom and with discharge openings for each column, a portion of said bottom under one of said columns being slightly higher in proximity to the tailings discharge than the remainder and said discharge openings being so positioned that the weights of any two columns of material when each extends to the level of its discharge opening will be substantially proportional to their horizontal cross-sectional areas, and means for applying intermittent impulses of a fluid to 75 the entire bottom of the separating chamber. 80

3. In an ore separator, a separating chamber having a reticulated bottom and provided with means for maintaining at least two columns of material thereon 85 communicating at a point near said bottom and with discharge openings for each column, said discharge openings being so positioned that the weights of any two columns of material when each extends to the level of its discharge opening will be substantially proportional to their horizontal cross-sectional areas, means for varying the relative height 90 of portions of the bottom of the separating chamber adapted to lessen the depth in proximity to the tailings discharge, and means for applying intermittent impulses 95 of air to the bottom of the separating chamber. 100

4. An ore separator, having a separating chamber provided with means for maintaining at least two separate columns of material communicating at their lower ends and 105 with discharge openings for each column, said discharge openings being so positioned that the weights of any two columns of material when each extends to the level of its discharge opening will be substantially proportional to their horizontal cross-sectional areas, a support for the separator, and means for tilting the separator on its support to vary the depth of the portion of one column adjacent to the tailings discharge 110 opening. 115

In testimony whereof, I have hereunto set my hand and affixed my seal in the presence of the two subscribing witnesses.
